HIGH-SPEED BENDING ROLLER MACHINE

Louis Illmer, Cortland, N. Y.

Application February 8, 1943, Serial No. 475,196

6 Claims. (Cl. 140—148)

The present improvements relate to a compact machine low in first cost and primarily arranged to expedite the straightening of a kinked or other initially deformed reelable metallic strand of round or flat profile by reversely crimping such work piece through a long succession of staggered bending rollers respectively carried upon non-rotating spindles and mounted in groups upon adjustably spaced rackbars having certain of their rollers axially inclined and otherwise adapted to treat said strand at a relatively fast rate to bring the product into a straightened kink-free condition.

Multifold pairs of rackbar components are herein cooperatively disposed abreast of each other in juxtaposed relation to shorten their combined overall length in comparison to an uninterrupted tandem assembly and thereby obviate the need for an abnormally long floor space. Driven guide sheave means may carry a common strand into endwise registry with several of such rackbar groups. The attainment of the contemplated accelerated rate of productive delivery, calls for the use of an appropriately extended number of roller spans to establish a serpentine strand path of requisite length. To minimize the resulting frictional drag, all bending rollers are preferably equipped with ball bearings or the like anti-friction race means and the treated strand positively kept out of direct sliding engagement with fixed supports. Identical apparatus may likewise be utilized to perform strand fatigue tests thereon.

The primary object of my invention is to devise an economical straightening or material testing machine of the indicated character in which a plurality of conjoined dual roller-carrying rackbars may be juxtaposed and compactly placed along side each other with certain roller axes inclined to each other and serviced by strand guide sheave means whereby to promote the rate of production, reduce overall floor space requirements and otherwise improve structural aspects.

Reference is had to the accompanying two sheets of drawings which are descriptive of alternative exemplifications, and in which:

Fig. 1 represents an elevational side view of a horizontal type of wire straightener, and Fig. 2 an end view thereof.

Fig. 3 is taken along 3—3 of Fig. 1 and in profile details a preferred style of sheave rim.

Fig. 5 as taken along 5—5 of Fig. 1, shows a profile assembly of my roller equipped rackbars, and Fig. 4 is a top view thereof.

Fig. 6 is taken along 6—6 of Fig. 1 to illustrate an alternative roller assembly.

Figs. 7 and 8 respectively reveal side and end views of an upright type of machine.

Fig. 9 is taken along 9—9 of Fig. 7 showing a further modification in roller rackbar disposition.

Fig. 10 diagrammatically depicts the bending action to which the crimped strand is subjected.

Referring in detail to Figs. 1 to 6, this horizontal type of straightener may comprise a skeletalized three-deck A frame including mated angle-iron leg extensions or corner posts such as 10A and 10B that may be bridged by the cross-beams 11, 12, and 13. Corresponding pairs of cross beams may be spanned by horizontal deck agencies such as 14A, 14B, and 14C. The pair of crooked posts 10B may each mount a journal bearing 16 to support the pulley shaft 17 thereacross. The strand guide sheave or grooved tractor pulley 18 may be carried upon said shaft and be sprocket driven by the chain 19. A high speed motor 20 may be upheld by the intermediate deck 14B and overhang the gear reduction box 21 to transmit power to said pulley. As revealed in Fig. 3, the bottom of such return pulley groove may be filled with a suitable lining such as the leather strip 22 to fortify the seated grip of its embracing strand or work piece 23 of comparatively flexible reelable material hereinafter more definitely identified.

A succession of similar but reversely inclined stationary carrier blocks 25A, 25B etc. may be alignedly mounted upon the top deck 14C and each of these several blocks are preferably kept comparatively short. As detailed in Fig. 5, each such block may provide for a beveled 45° face upon which is imposed the conjoined dual parallel rackbars or block components 26 and 27 of cold rolled flat stock. One such bar may be affixed to said face by a rivet or the like securing means 28 while its mated bar is made slidable to afford an adjustable gap G therebetween. When reversely assembled as in Fig. 1, the respective oblique roller axes of alternate blocks 25A and 25B will assume the perpendicular relationship indicated by dotted outline in Fig. 5.

Each pair of mated bars may be transversely reamed in aligned registry and have a stanchion 29 bridgingly entered therethrough as shown. One stanchion end may be tightly doweled in place at 30 and a projecting end region may be kept slidable in crosshead guide fashion. An applied lock nut 31 allows of forcibly thrusting 55 these opposed bars toward each other to sinuous-

ly deflect the interposed strand 23. All of said nuts are placed within convenient reach to facilitate a uniform change in the setting of the bar gap G. Such parallelly retained bars are respectively equipped with a separate series of rollers namely 32 or 33 that are uniformly spaced axially at a span distance marked S, the rollers on the respective bars being relatively staggered in the Fig. 4 manner.

Each roller is preferably provided with interposed ball bearings 34 (see Fig. 10) circumscribing an overhanging roller spindle 35 whose affixed shank end may be driven into the bar thereof. The functional behavior of such combined staggered roller series may be traced by further reference to Fig. 10. Assuming all the bar gaps G to have been similarly adjusted to suit the particular quality and size of wire, said roller will distort such strand into an appropriate serpentine path. Considered as a continuous beam, each half span or sectional length $S/2$ becomes laterally loaded by the roller thrust P with a consequent single-action sag or semi-deflection d . Such thrust sets up counteracting divergent pulls marked T which impart longitudinal stretch to the crimped wire. The radially outer crown region of each successively crimped wire portion is thereby subjected to combined bending and tension stress of sufficient intensity to dominate its initially crooked deformation and thus correct any irregular set thereof.

A fairly definite relation usually prevails between the ultimate tensile strength of ferrous stock and its Brinell hardness number when held to less than 400 in value. Under extreme temper conditions, the corresponding elongation for very hard frangible steel becomes substantially nil and carries its elastic limit into so close proximity to the accompanying ultimate tensile strength as to afford only an insignificant marginal stress range or leeway in which to rectify such material without the likelihood of imminent rupture. For so-called hard ferrous wire, the elastic limit does not approach its corresponding tensile strength to a like degree and it is such relatively softer than extremely tempered ferrous stock which my straightener is particularly intended to handle effectively at high linear velocity. To effect complete and generally acceptable straightening results, the aforesaid combined bending and tension fiber intensity needs to be reversely carried well beyond its elastic limit in planes at right angles to each other so as by proper stretch, to utilize a substantial portion of the available gross elongation of the treated strand material without undue encroachment upon the remaining scant stress leeway.

The motive effort or bending work required to advance the wire axially through any one span length S is substantially proportionate to the product of the thrust P by twice the corresponding semispans deflection d , plus the accompanying frictional roller drag. The use of full fashioned ball bearings 34, serves to materially ease such supplemental drag. A relatively long series of spans equipped with axially inclined rollers, are needed to accomplish present purposes even when sharply crimping the wire about a short radius of curvature marked R in Fig. 10. Interposed wire grip means are therefore provided to repeatedly induce renewed motivation of the treated wire and thereby suppress the resulting total stress within amply safe limits against rupture.

My machine is especially adapted to speed up

reelable wire to about 300 or 500 feet per minute in comparison to a commercially prevailing straightening rate of approximately one hundred feet per minute for hard ferrous stock. The

5 ball bearing rollers may herein be kept to a small low cost size and run at moderate rotative speed for which the peripheral ball velocity may readily be held well below critical running limits. The various sheave journals may likewise be ball 10 bearing equipped but where the journal diameter is kept small in relation to the diametral sheave dimension, such refinement becomes non-essential.

The number of roller spans required for complete 15 straightening are substantially independent of the treated wire diameter. A requisite number of such roller spans if extended in aligned tandem disposition plus space for the pinch roller drive means, usually results in an abnormal 20 overall floor space length. By compactly crowding sectionalized groups of my fragmental roller paths abreast in alongside relation and having strand guide sheave means interposed between certain block ends as practiced herein, their combined 25 juxtaposed length may be considerably contracted to fall into a frame structure whose major floor space dimension L (see Fig. 1) may be kept materially shorter than the aggregate overall length of a corresponding number of roller spans 30 when placed in tandem alignment.

Wires of smaller diametral size need a proportionately greater crimp deflection d . Where larger reelable wire sizes are to be treated, the sheave diameter may be correspondingly increased. 35 It will be observed that the sheave radius is purposely kept considerably larger than the crimping radius R to obviate excessively setting the wire while being carried about the tractor pulley 18. In order to multiply the tractive 40 grip of the seated wire 23, it may be wound around such pulley groove through more than one convolution.

The bottom deck 14A may be equipped with an additional series of alternately assembled carrier 45 blocks 38A, 38B, etc. As detailed in Fig. 6, these blocks also have their respective roller axes disposed perpendicularly to each other but in a vertical and dotted roller outline whereby to successively 50 impose bending stress in dihedral planes that intersect the wire axis. Opposite ends of mated rollers are reversely provided with a single stop flange such as 36A between which to center the advancing strand against unwanted lateral shift. 55 Such disposition in combination with the previously defined top deck blocks, serves to uniformly and repeatedly subject the treated wire to frequent successive crimps inclined at 45° to each other. By substituting the Fig. 6 style of block throughout 60 for the Fig. 5 block, my machine is rendered suitable for treating flat wire or the like ribbon stock.

Referring further to Fig. 1, opposed complementary pinch rollers 39 and 40 may be bracketed 65 to a frame member to drag the leading end of the interposed strand through the last entered blocks 38A, 38B etc. One or both of such pinch rollers may be driven by the chain 41 to run in unison with the motor 20. The respective roller perimeters may be adjustably urged into tight gripping contact with said strand by the use of a screw controlled thrust spring 42.

A similar idler impress roller 43 may be arranged to fortify the wire grip with respect to the 75 pulley seat 22. The use of multiple strand driver

means respectively interposed behind each group of roller blocks, serves to reduce the accumulative frictional drag imparted to a wire already highly stressed by crimp drag.

Figs. 7 to 9 disclose a vertical or upright type of machine in which the treated strand 45 is helically threaded in winch fashion over plural bottom sheaves 46A, 46B and 46C. These may be mounted upon a common lower cross shaft or axle 47 in association with staggered top sheaves 48A and 48B of identical diameter that are fixedly mounted upon the companion upper shaft 49 and which shaft is shown axially spaced from its mate 47 by a certain pitch distance. Said shafts may be sprocket interconnected by the chain 50 to run in unison. Unidirectional motorized means 51 may chain drive the primary shaft sprocket 52 as shown.

The intermediate apertured platform or deck agency 53 may have demountably affixed thereto, multiple erected companion roller blocks such as offset members 54A or 54B. The components of each such companion block may comprise pairs of roller equipped rackbars 56 and 57 respectively that may be seated perpendicularly upon the divergent base faces 44 in the Fig. 9 manner.

The first sheave 46A may be loosely carried upon its shaft to freely guide the incoming wire 45 upwardly through the opposed rollers of the depending and erected blocks 55A and 54A, thence over the first top sheave 48A and helically downward through the offset outturned rollers of the registering blocks 54B and 55B until the leading wire region is brought into embrace with the last winch sheave 46C. In order to maintain undeviating alignment on part of the advancing strand, the affixed end of each such block component may be appropriately tilted by an interposed cant block 59 or the equivalent thereof providing for the wedge angle A.

Prior to reaching the first tractor sheave 48A, the treated wire will have been tautly dragged through two pairs of blocks bars which in turn elevates its initial slack tension and thereby augments its frictional grip while passing over said driven top sheave. In a like manner, each block interposed sheave may independently impart a renewed impetus to the advancing wire in order to leave the respective winch sheaves under substantially equalized drag tension.

To maintain adequate traction around the last entered sheave 46C without undue slippage, the emerging end region of the work piece 45 may be subjected to a supplemental final drag by the use of a refined pinch roller mechanism. As shown in Figs. 7 and 8, this comprises a pair of driven span rollers that may be conjointly rotated by the axially spaced spur gears 60 and 61. The armature shaft of an independent fractional H. P. auxiliary motor 62 provides for a gear intermeshing pinion 63 that may unidirectionally drive both span rollers at a peripheral velocity considerably greater than a prescribed rate of wire travel. One leg of a pivotally mounted bell crank 64 carries a crimp roller 65 and the other leg may be adjustably shifted by the screw 66 to yieldably thrust said crimp roller between a single pair of span rollers to regulatably crimp the interposed wire 45 in the Fig. 10 fashion. By roller slippage, such compensating drag device prevents pronounced slackening and maintains augmented wire traction. Similar drag roller means may also be applied to the incoming strand end region.

Furthermore, when the bell crank 64 is ap-

propriately adjusted, the crimp imparted by the roller 65 may be made to compensate and substantially correct for any partial set that may result from stretchingly winding the wire about the last sheave 46C. Such delivered straight wire may be automatically severed into predetermined lengths by the use of conventional cut off means.

The number and diametral size of my winch sheaves may be altered to suit requirements. The drive power needs per foot of completed product is herein kept exceptionally low by the deliberate avoidance of any direct sliding drag on part of the work piece with respect to any stationary guide element.

As will be obvious, Fig. 1 could readily be modified by introducing a supplementary pulley (such as 48B of Fig. 7) in axial parallelism with the pulley 18 to allow the delivery end of the wire 23 to be looped upwardly over the top deck 11, the lower rackbars 38A and 38B then being bodily transferred to the top deck 11 to lie alongside the rackbars 25A and 25B in the Fig. 8 manner. The bottom deck 13 may thereby be eliminated and the treated wire would leave its last entered rackbar in the same direction as the incoming wire as in Fig. 7.

As an additional use to which my machine may be put, the respective terminals of open-ended strand material may be spliced together to constitute a dragged loop as schematically indicated in Fig. 7 by the numeral 68. When such endless work piece is unidirectionally driven by the motor 51 for fatigue testing purposes, said loop may be made to continuously pass through numerous crimping spans until ultimate rupture is brought about. By recording the time of such run, a close determination may be had of the number of reverse bending repetitions required to reach the endurance limit for such tested material.

Not only can the stress intensity range be selectively modified by altering the gap G of the several component roller bars when used as a testing machine, but the rate of stress application can be changed by correspondingly restricting

the strand travel velocity.

The foregoing disclosure will it is believed, make evident to those skilled in this art, the more outstanding advantages afforded by my improved apparatus and system, it being understood that certain underlying structural principles are capable of incorporation in certain other embodiments devoid of strand reversing guide means, all without departing from the spirit and scope of my invention heretofore described and more particularly characterized in the appended claims.

I claim:

1. In a bending machine adapted to reversely crimp a reelable metallic strand or the like comparatively flexible material while being advanced longitudinally, said machine comprising a plurality of similar carrier block means that are disposed abreast each other into a contracted juxtaposed length shorter than the aggregate overall length of all block means, each such block means including conjoined dual rackbars respectively mounting a series of axially interspaced bending rollers therealong and which mated series are staggered to constitute successive crimping spans through which to subject an advancing strand to repeatedly reversed bending stress imposed along a common plane that substantially coincides with the strand axis, certain axes of the rollers embodied in one such carrier block means being angularly inclined

with respect to the roller axes in another block means whereby to successively impose bending stress in dihedral planes in a single pass through all of the plural block means.

2. In a straightening machine adapted to reversely crimp a reelable metallic strand of the like comparatively flexible material while being advanced longitudinally, said machine comprising a plurality of similar carrier block means that are disposed abreast each other into a contracted juxtaposed length shorter than the aggregate overall length of all block means, each such block means including conjoined dual rack-bars respectively mounting a series of axially interspaced bending rollers therealong and which mated series are staggered to constitute successive crimping spans through which to subject an advancing strand to repeatedly reversed bending stress imposed along a common plane that substantially coincides with the strand axis, certain axes of the rollers embodied in one such carrier block means being angularly inclined with respect to the roller axes in another block means, and sheave means serving to guide the advancing strand from one end of said one block means to the opposed end of the aforesaid another block means whereby to completely straighten the stand in a single pass through said machine.

3. In a straightening machine adapted to crimpingly treat an elongated work piece of comparatively flexible material while being advanced longitudinally, said machine comprising a plurality of similar carrier blocks whose corresponding ends are disposed abreast each other into a contracted juxtaposed length shorter than the aggregate overall length of all carrier blocks, each such block being provided with dual rack-bar means respectively equipped with a series of axially interspaced bending rollers and which mated series are arranged in staggered relationship to constitute successive spans therebetween through which to continuously crimp the advancing work piece, and strand reversing sheave means interposed between certain corresponding block ends and arranged to guide the work piece from one of said block ends in a contrawise direction into the other corresponding block end.

4. In a bending machine adapted to crimpingly treat a reelable metallic strand or the like comparatively flexible material while being advanced lengthwise, said machine comprising a pair of rotatable sheaves having a strand wound therearound in multiple loops and serving to advance said strand longitudinally onward, and two carrier block means disposed abreast each other within a contracted juxtaposed length shorter than the combined overall length of both said block means, each such carrier block means being provided with conjoined dual rackbars respectively mounting a series of axially interspaced bending rollers therealong and which

mated series are staggered to constitute successive crimping spans through which to subject a dragged strand to repeatedly reversed bending stress imposed along a plane that coincides with the strand axis, one such carrier block means being arranged to treat a certain strand loop and the other block means being arranged to treat an adjacent loop and having the bending planes of the respective block means inclined angularly.

5. In a bending machine adapted to crimpingly treat a reelable metallic strand or the like comparatively flexible material while being advanced lengthwise, said machine comprising a pair of rotatable sheaves respectively mounted upon substantially parallel shafts that are interspaced at a certain axial distance and about which sheaves the strand is grippingly wound in multiple loops, and a plurality of carrier block means cooperatively arranged abreast each other to treat different loops and disposed into a contracted juxtaposed length shorter than aggregate overall length of all such block means, each such carrier block means being provided with conjoined dual rackbars respectively mounting a series of axially interspaced bending rollers therealong and which mated series are staggered to constitute successive crimping spans for subjecting the looped strand to repeatedly reversed bending stress, said sheave means when rotated in unison serving to drag the strand through the aforesaid aggregate overall length and which length is materially longer than the stipulated axial distance.

6. In a unitary bending machine adapted to completely straighten reelable wire or the like strand in a single pass, said machine comprising an erected frame work provided with superimposed deck agencies, a sheave carrying axle mounted upon one such agency and which sheave is adapted to have reelable wire grippingly wrapped about a portion of its perimeter, a motorized gear reduction box carried by said frame work and serving to drive said axle for longitudinally advancing the wire, and a plurality of carrier block means upheld by the other of said agencies to cooperate with the advanced wire and which block means are disposed abreast each other into a contracted juxtaposed length shorter than the aggregate overall length of all block means, each such carrier block means being provided with conjoined dual rackbars respectively mounting a series of axially interspaced bending rollers and which mated series are staggered to constitute successive crimping spans through which to subject the advancing wire to repeatedly reversed bending stress imposed along a plane that substantially coincides with the wire axis, certain of the roller axes embodied in one such block means being angularly inclined with respect to those embodied in another block means.

LOUIS ILLMER.
